UNITED STATES PATENT OFFICE

2,104,035

STOKER FOR LOCOMOTIVES

William Thompson Hanna, Cincinnati, Ohio

Application April 5, 1929, Serial No. 352,761
Renewed November 21, 1935

11 Claims. (Cl. 110—101)

This invention relates to stokers in general but more particularly to stokers for use on locomotives and the like.

One of the objects of the invention is to provide a simple, compact and durable stoker mechanism which is economical and efficient in operation.

Another object is to provide a stoker mechanism of the above character which materially enhances the flow of fuel therethrough and prevents any back pressure.

Another object is to provide a stoker of the above character in which a rising column of fuel is broken up and spread out prior to its delivery to a firing opening and a fire box.

Another object is to provide a stoker mechanism of the character above described which is not only arranged to spread out fuel just prior to its delivery to the firing opening, but which also materially aids the movement of the fuel toward the firing opening.

A further object of the invention is to provide a stoker mechanism of the above character which permits of ready observation of the flow of fuel therethrough and unobstructed hand firing, as may be required under certain circumstances.

These and other apparent objects and advantages are obtained by the means described in the following specification and shown in the accompanying drawings wherein:

Fig. 1 is a side elevation partly in section, showing an application of the principles of the invention to a locomotive and tender the gear 30 being omitted.

Fig. 2 is an enlarged vertical sectional view of the fuel supply housing and the delivery end of the transfer conveyor, taken on the line 2—2 of Fig. 4.

Fig. 3 is a plan view partly in section of the mechanism shown in Fig. 2.

Fig. 4 is a sectional view taken substantially on the line 4—4, Figs. 2 and 3.

Referring to the drawings, 10 represents the back head of a locomotive fire box having the usual grate bars 11 and firing opening 12. Embracing this opening and rigidly mounted on the outer face of the back head is a fuel conditioning or supply housing 13 which carries, at its lower end, an extension or fuel inlet 14, through which the housing chamber is extended to encompass the delivery end of a transfer conveyor 15 revolvably supported in a cylindrical conduit 16 coaxing with a tender hopper 19 (Figure 1).

The forward end of the conduit 16 is provided with a universal connection with the extension

14 below the deck 17 of the locomotive. This connection comprises a spherically shaped member 16—a secured to the end of the conduit 16 and journaled in a spherically shaped recess 14—a in the end of the extension 14. The housing 13 may be provided with an opening 13—a in the rear wall thereof in alignment with the firing opening 12, to permit hand firing. This opening 13—a may be encompassed by a fire door plate as 13—b upon which may be mounted any suitable type of door.

The conveyor 15 has a suitable operative connection (not shown) with a conveyor 18 revolvably mounted within the tender hopper 19 below the tender deck 20. This conveyor 18 is actuated by a suitable power device 21 on the locomotive, through the medium of a telescopic shaft 22 universally connected thereto at 23 and also universally connected with a shaft (not shown) journaled upon the tender hopper and having a geared connection with a gear 23—a secured to the rear end of the conveyor 18.

The form of the housing 13 and its extension 14 is of such a character as to receive the fuel from the delivery end of the conveyor 15 and to elevate and deliver it to a feeding, spreading, distributing or regulating device and at the same time allow an unusually unrestricted flow of the fuel and prevent the building up of any back pressure. In other words, the connection which the extension or fuel inlet 14 forms between the conduit 16 of the fuel supply housing 13 is such that there is substantially no restriction to the flow of fuel from the place where it leaves the end of the screw conveyor 15 until it emerges from the extension 14 into the housing 13. The spreading device comprises two rotary distributing vanes or feeders 24 and 25, suitably journaled in a rear wall of the housing 13, and preferably located directly above the passage 14 in the lower portion of the housing through which the coal is elevated. (The term "rear wall" refers to that wall away from the firing opening 12, and hereinafter the phrase "forward motion of fuel" refers to the motion of fuel toward the firing opening.) As shown in Figures 2 and 3, the feeders 24 and 25 are, in effect, tapered worms, mounted on conically shaped axes. I have found this construction has many advantages and is of great practical value. However, under certain conditions of operation, I may find it desirable to vary the construction of the feeders 24 and 25 by making certain minor changes, such as, for example, by changing the slope of the vanes. But with these changes I do not effect the novel results which

80

- these worms 24 and 25 bring about, and which will be described hereinafter. As shown in the present embodiment, the axes of the feeders 24 and 25 diverge toward the firing opening 12. 5 With this arrangement of the feeders or spreaders 24 and 25 I accomplish many new and highly desirable results as will be pointed out herein-after. While I have found this arrangement highly advantageous, and that under general 10 conditions of operation it gives the most effective and practical results, under certain conditions of operation I may prefer to vary the arrangement by changing the angle between the axes to make them parallel or otherwise. 15 Rotary motion is imparted to the vanes or feeders 24 and 25 from the power device 21 through a driving connection. This connection may be of any suitable character but in the present embodiment comprises a telescopic shaft 26 universally 20 connected at one end with a suitable shaft 27 supported in the rear wall of the housing 13 and having a gear 28 which meshes with gears 29 and 30 secured respectively to the hub portions of the feeders 24 and 25. The opposite end of the shaft 25 25 has a universal connection with the shaft 31 journaled upon the tender hopper 19 and having secured to its rear end a gear 32 which meshes with the gear 23—a. With this unusual arrangement of the spreaders 24 and 25 in the housing 13, 30 I am enabled to provide them with driving gears 29 and 30 which mesh with a single driving gear 28. The cross section of the housing extension 14, and also that portion of the housing 13 immediately adjacent such extension, is substantially circular in contour. The cross sectional dimension 35 of the conduit extension 14 is of the smallest diameter at that portion designated 14—b, this portion being substantially of the same diameter as the inside diameter of the member 16—a. 40 Immediately forward of the point 14—b, the inside diameter of the extension 14 is suddenly enlarged as shown in Fig. 2. This serves to give the volume of fuel a sudden relief at the time it begins its upward movement through the conduit 14 and 45 facilitates the elevation of the fuel. Furthermore, the cross sectional area of the conduit forward and upward from the point 14—b increases and this also facilitates the more efficient elevating of the fuel to the feeding device. As shown in 50 Figures 2, 3, and 4, that portion of the housing 13 which joins the conduit or extension 14 rapidly increases in its cross-sectional area from the conduit 14 to the spreading devices 24 and 25. With this rapid expansion of the fuel inlet part 55 of the housing 13, I provide for an even free flow of the fuel upwardly, and so further guard against any tendency of the fuel to pack or otherwise collect in the passage from the conveyor conduit 16 to the firing opening 12. 60 As shown in Figure 2, a lower portion 42 of the housing 13 has an upper edge portion 40 adjacent the lower edge 41 of the firing opening 12. The edge 40, in effect, forms a ledge over which fuel passes flowing from the housing 13 to the firing 65 opening 12. Positioned in the lower portion of the firing opening 12 is a blast chamber 33 and a distributor plate 34 which serve to effectively distribute the fuel to all parts of the fire bed. Any suitable blasting device or distributor plate may be used in combination with the other elements of this type 70 of stoker mechanism. 75 The tender hopper 19 is equipped at its delivery end with a crushing device 35, preferably arranged adjacent to and partially encompassing

the conveyor 18. This crushing device may be of any suitable character that would efficiently break up large lumps of fuel and reduce them to a size that would readily pass through the housing and feeding device. 5

The power device 21, as shown, is similar in construction to that disclosed in my U. S. Patent 1,577,462, in which the primary transmission element comprises a rack and pinion and this form has proven entirely satisfactory, but it will be understood that any other suitable forms of power device and transmission elements may be used for this purpose. 10

In the operation of this stoker mechanism the coal passes through the deck of the tender into the 15 trough of the tender hopper 19 and is conducted by means of the conveyor 18 to the crushing device 35 where any abnormally large lumps of coal may be broken up to normal size. The fuel is then delivered by the conveyor 18 to the transfer conveyor 15 which conducts it to the ascending conduit formed by the housing extension 14 and the lower portion 42 of the housing 13. As hereinbefore described, the conduit 14 and the lower portion 42 of the housing 13 rapidly increase in cross- 20 sectional area from the points at which the conduit 14 joins conduit 16, and thus the column of fuel entering the conduit 14 and the lower portion of the housing 13 from the conduit 16, continues to flow upwardly, impelled by the conveyor 15 for 25 a short distance without encountering any resistance because the expanding walls of the conduit formed by the extension 14 and the housing 13 relieve any pressure which may tend to build up between the column of fuel and the walls. The 30 column of fuel continuing its upward path ascends to the feeding or spreading devices 24 and 25 which serve to break up the mass of the rising column of fuel and spread it in the fuel conditioning housing 13. Further, these rotating vanes 35 24 and 25 tend to serve as a continuation of the conveyor 15 by pushing and carrying the fuel forward to cause it to flow over the edge 40 into the firing opening 12 and on to the blast chamber 33 and distributing plate 34 and above the level of 40 the fire. The blast chamber 33 distributes the fuel and prepares it for reception by the distributor plate 34, from which it is distributed over 45 the fire by means of blasts of steam emitting from the blast chamber. 50

As hereinbefore pointed out the feeding or spreading devices 24 and 25 accomplish many new results. For example, I have found that with this arrangement of the spreading devices 24 and 25, I can thoroughly and effectively 55 spread or level the fuel entering the housing 13 whether the fuel is wet or dry, packed or loose.

This leveling of the fuel before it reaches the edge 40 and the blast chamber and distributing plates 33 and 34 respectively is highly desirable 60 for an efficient operation of the distributing plates, for if the fuel does not enter the firing opening distributed evenly over the edge 40 it may fall in large uneven lumps on to the distributing plate, and in such a way as to practically prevent any effective action by the blast chamber to distribute the fuel to the far and near corners of the fire bed. 65

Another advantage of the arrangement of the spreaders 24 and 25 which I have shown in this 70 embodiment is that they form no obstacle to the flow of fuel emerging into the housing 13 from the conduit 14, but rather serve to level and forward the fuel to the firing opening 12.

While I have shown and described a particular 75

construction embodying the novel features of this invention, it is to be understood that this is for the purpose of illustration only and that this construction may be variously modified and altered without departing from the spirit and scope of the invention as set forth in the appended claims.

I claim:

1. In combination with a fire box having a firing opening, a stoker mechanism including a housing having a delivery opening communicating with said firing opening, the lower edge of said delivery opening forming a ledge over which fuel flows in passing to said firing opening, said housing also having a fuel supply inlet; and rotatable spreading and feeding means inclined upwardly from the rear of said housing to positions immediately adjacent the respective ends of said ledge, for spreading fuel entering from said fuel supply inlet, in said housing and causing it to flow over said ledge in a regulated stream.

2. In combination with a fire box having a firing opening, a stoker mechanism including a housing having a delivery opening communicating with said firing opening, the lower edge of said delivery opening forming a ledge over which fuel flows in passing to said firing opening, said housing also having a fuel supply inlet; and a plurality of worms mounted for rotation in a rear wall of said housing and inclined upwardly to positions immediately adjacent said ledge, for aiding and regulating the flow of fuel entering from said fuel supply inlet over said ledge.

3. In combination with a fire box having a firing opening, a stoker mechanism including a housing having a delivery opening communicating with said firing opening, and the lower edge of said delivery opening forming a ledge over which fuel flows in passing to said firing opening; said housing also having a fuel supply inlet; and at least one rotatable tapering worm inclined upwardly from the rear of said housing to a position immediately adjacent said ledge, for aiding and regulating the flow of fuel entering from said fuel supply inlet, over said ledge.

4. In a stoker mechanism the combination with a fire box having a fuel entrance of a conduit provided with means for moving fuel from a source of fuel supply to said entrance, the upper end of said conduit embracing said entrance and being provided with a ledge over which fuel flows to said entrance, means for distributing fuel fed to said entrance upon and over the fire, and a pair of tapered worms mounted in the wall of said conduit away from said entrance and extending forwardly from a plane below said ledge to positions immediately adjacent the ends of said ledge whereby fuel moving up through said conduit is caused to flow over said ledge and through said entrance in a regulated stream, said rotary worms acting on the side and rear portions of said stream.

5. In a stoker mechanism the combination with a fire box having a fuel entrance of a conduit provided with means for moving fuel from a source of fuel supply to said entrance, the upper end of said conduit embracing said entrance and being provided with a ledge over which fuel flows to said entrance, means for distributing fuel fed to said entrance upon and over the fire, and fuel conditioning and regulating means interposed between said fuel moving means and said fuel distributing means comprising a pair of rotary worms mounted in the con-

duit and extending from the wall of said conduit away from said entrance and from positions below said ledge to positions slightly above said ledge whereby said worms condition and regulate and elevate said fuel.

5

6. In a stoker mechanism the combination with a fire box having a fuel entrance of a conduit provided with means for moving fuel from a source of fuel supply to said entrance, the upper end of said conduit embracing said entrance and being provided with a ledge over which fuel flows to said entrance, means for distributing fuel fed to said entrance upon and over the fire, and a pair of worms mounted in the wall of said conduit away from said entrance and extending forwardly from a plane below said ledge to positions immediately adjacent the ends of said ledge whereby fuel moving up through said elevating conduit is caused to flow through said entrance in a regulated stream, said rotary worms acting on the side and rear portions of said moving stream.

10

7. In a stoker mechanism the combination with a fire box having a fuel entrance of a conduit provided with means for moving fuel from a source of fuel supply to said entrance, the upper end of said conduit embracing said entrance and being provided with a ledge over which fuel flows to said entrance, means for distributing fuel fed to said entrance upon and over the fire, and fuel conditioning and regulating means mounted in said conduit including a rotary tapered worm extending from a position at the rear wall of said conduit not above the line of said ledge to a position immediately adjacent said ledge.

15

8. In a stoker mechanism, the combination with a fire box having a firing opening, of a transfer conduit for conveying the fuel from a source of fuel to the firing opening, said transfer conduit being enlarged at its delivery end and embracing the firing opening and having a hand-firing opening in a rearward wall thereof and aligned with said firing opening, fuel moving means for moving fuel in said conduit, fuel distributing means associated with said firing opening for distributing fuel fed thereto in the fire box, a rotary worm mounted in the enlarged portion of said conduit and below the hand-firing opening and extending transversely of the enlarged portion of the conduit, and forwardly from the rear thereof, said worm aiding the presentation of the fuel to the fuel distributing means.

20

9. In a stoker mechanism, the combination with a fire box having a firing opening, of a transfer conduit for conveying the fuel from a source of fuel to the firing opening, said transfer conduit embracing the firing opening and having a hand-firing opening in a rearward wall thereof and aligned with said firing opening, fuel moving means for moving fuel in said conduit, fuel distributing means associated with said firing opening for distributing fuel fed thereto in the fire box, and fuel regulating means comprising a pair of rotary tapered worms mounted in the rear wall of the conduit below the hand-firing opening and extending upwardly from a plane below the lower edge of the firing opening to points adjacent the respective ends thereof for regulating presentation of the fuel to the fuel distributing means.

25

10. In a stoker mechanism, the combination with a fire box having a firing opening of a conduit for conveying fuel from a source to said firing opening, the upper end of said conduit embracing said opening and having adjacent the lower edge of the firing opening a horizontal ledge over which fuel flows through said firing opening.

30

40

45

50

55

60

65

70

75

means for distributing fuel fed to said opening upon and over the fire, and fuel conditioning and regulating means mounted in said conduit including a rotary tapered worm extending from a position at the rear wall of said conduit not above the horizontal line of the ledge of said conduit to a position immediately adjacent said ledge.

5 11. In combination with a fire box having a firing opening, a stoker mechanism including a 10 housing having a delivery opening communicating with said firing opening, and the lower edge

of said delivery opening forming a ledge over which fuel flows in passing to said firing opening; said housing also having a fuel supply inlet; and at least one rotatable tapering worm disposed within said housing and extending upwardly from a point rearward of and below said ledge to a position immediately adjacent said ledge for aiding and regulating the flow of fuel entering from said fuel supply inlet over said ledge.
